UNITED STATES PATENT OFFICE.

RESCUE B. PAGE, OF LOS ANGELES, CALIFORNIA.

FOLDING BED.

1,087,679.

Specification of Letters Patent. Patented Feb. 17, 1914.

Application filed February 27, 1913. Serial No. 751,150.

To all whom it may concern:

Be it known that I, RESCUE B. PAGE, a citizen of the United States, residing at Los Angeles, in the county of Los Angeles and 5 State of California, have invented new and useful Improvements in Folding Beds, of which the following is a specification.

My invention relates to improvements in folding beds of the type of bed adapted to 10 fold or swing upwardly into a recess formed in a structure, and the main object of my invention is to construct a bed of the character described of simple form and construction which may be easily operated into 15 raised or closed position or into lowered or open position.

Another object of my invention is to provide means whereby the recess above the bed, when in lowered or open position, may 20 be automatically closed during the downward movement of the bed by an improved operating means of simple construction.

Referring to the drawings, which are for 25 illustrative purposes only: Figure 1 is a perspective view of a bed embodying a form of my invention, showing the bed in lowered or open position. Fig. 2 is a side elevation partly in section of the bed shown in Fig. 1, drawn at a reduced scale. Fig. 3 is 30 a sectional view on line x^3-x^3 Fig. 2.

In the drawings, I have illustrated a bed 35 embodying a form of my invention as adapted to a recess built into a dwelling, but it is understood that my invention is not limited to such an adaptation, the bed being adapted to be operated in connection with any 40 form of structure provided with a suitable recess, in which case the structure comprises a fixed member and the bed body a movable member.

In the drawings, 1 designates a recess having 45 a rear wall 2 which extends from a top wall 3 to the floor 5 of a room. The front of the recess is faced with a frame consisting of a top member or plate 6, jambs 7, and a sill 8, which sill extends across the recess 50 on the floor 5 of the room. The bed body consists of a bottom member 11, side rails 12, head 13 and foot board 14, the bottom 55 member extending outwardly beyond the side rails 12 and the foot board 14, as indicated at 15. The head 13 of the bed is preferably provided with weight means for counterbalancing the bed which, in the present form shown, consists of cement indicated at 16, the top of the same being covered with

a cap 17 consisting of a board which extends across the top of the head from side to side thereof. A portion of the head 13 is cut away to form a groove 18 therein, over 60 which groove an extension 20 of the bottom member 11 of the bed projects. The foot portion of the bed when in lowered position, as shown in Fig. 1, is supported on two brackets 21, and the head portion of the bed 35 is supported on radius rods 22, the lower ends of which are mounted on pins 23 secured in L-shaped bars 23' mounted in fixed position on the side boards 12 of the bed. The upper ends of the rods 22 are threaded 70 and extend through toes 24 formed on the lower end of arms 24', the upper ends of which arms 24' are turned outwardly and rotatably mounted in brackets 25, which brackets are secured to the side walls of the 75 recess 1 in any suitable manner. The height or proper position of the head of the bed is regulated by means of nuts 26, one of which is placed upon the threaded end of the rods 22 above and below the toe of the arms 24'. 80

Guide means are provided for directing the movement of the bed during the operation of raising and lowering the same which consist of guides or rails 28, there being one rail 28 at each side of the head of the bed 85 within the recess 1. Each rail 28 is pivotally connected at its upper end by means of a bolt 29 to the respective sides of the recess, and the rails 28 extend downwardly and rearwardly from such pivotal point of the 90 same to the floor of the recess, where the position of the lower end of the rail may be adjusted by means of a bolt 30, the threaded end of which extends forwardly from the rail 28 through a bracket 31, to which the 95 same is secured by means of nuts 32. Mounted on each bar 23' is a roller 34 adapted to engage a metal plate or strap 35 on the face of the respective rails 28, which rails are each provided with a notch 36 into 100 which the rollers 34 are adapted to seat themselves when the bed is in lowered or open position.

The closure means for the portion of the recess 1 above the bed consists of a paneled 105 frame or plate 38 pivotally supported at a point above the lower edge thereof by means of pins 39, which pins 39 are fixed in brackets 40 on the back of the plate 38 at each side thereof, the outer ends of the pins 39 at each 110 side of the plate 38 extending through a flattened portion 41 of the rods 22. The flat

portion 41 of each rod is bent out of alignment of the major portion of the rod 22 and extends through a cutaway portion 42 of the plate 38. The flat portion 41 of the rods 22 5 is bent in the form shown so that the cutaway portion of the plate may be reduced to a minimum size. The upper end of the plate 38 is guided during the raising or lowering of the bed by means of tracks 43 secured to the end walls of the recess 1, which 10 tracks are engaged by means of rollers 44 mounted one at each end of the plate on the back thereof.

While I have not shown any bedding, it 15 is well understood that bedding may be placed upon the bed and retained thereon in any of several well known ways.

The bed is operated as follows: Assuming the bed to be in closed position, as shown in 20 Fig. 2, it is to be noted that the bottom member 11 of the bed extends over the top member 6 of the frame of the recess, and that the extension 20 of the bottom 11 extends over the sill 8 of the same. In this position the 25 closure plate 38 stands away from the bed in the rear thereof within the recess, being supported on the rods 22. By means of the brackets 21 the foot of the bed may be pulled outwardly and downwardly, during which 30 movement the weight of the bed is supported on the radius rods 22, the lower ends of which swing outwardly; at the same time the rollers 34 travel upwardly on the respective tracks 28 causing the bed to swing 35 bodily forward out of the recess until the bed assumes the position shown in Fig. 1. As the rods 22 swing forwardly, the closure plate 38 is carried forwardly, the upper end of which is guided in its movement by the 40 rollers 44 and tracks 43 until the upper end of the plate 38 engages behind the top member 6 of the frame of the recess, at which time the lower end of the plate 38 is seated on the cap 17 of the head of the bed, there-

by completely closing the opening in the 45 recess, it being understood that the plate 38 is wide enough to engage behind the jambs 7. The bed is raised into closed position by raising the foot of the bed, the bed swinging on the rods 22 and carrying the closure 50 plate out of the way of the bed into the original position shown in Fig. 2, the bed being guided into proper relation with the facing of the recess by means of the tracks 28 and the rollers 34. 55

What I claim is:—

1. A structure having a recess, a bed body, a pair of rods pivotally connected at their upper ends to said structure within said recess and pivotally connected at their lower 60 ends to said bed body, supporting means on said bed body for the outer end of said bed body, means for limiting the swinging movement of said rods, and closure means pivotally mounted on said rods adapted to close 65 the recess above said bed body when in lowered position.

2. A structure having a recess, a bed body, a pair of rods pivotally connected at their upper ends to said structure within said recess and pivotally connected at their lower 70 ends to said bed body, supporting means on said bed body for the outer end of said bed body, means for limiting the swinging movement of said rods, closure means pivotally 75 mounted on said rods adapted to close the recess above said bed body when in lowered position, and guide means mounted within said recess for the upper end of said closure means. 80

In testimony whereof, I have hereunto set my hand at Los Angeles, California, this 17th day of February, 1913.

RESCUE B. PAGE.

In presence of—

FRANK L. A. GRAHAM,
LORRAINE E. DURROW.
